CLAIM

The ornamental design for a steering wheel module for automobile, as shown and described.

DESCRIPTION

1. Steering wheel module for automobile
1.1 is a perspective view of a steering wheel module for automobile embodying our new design;
1.2 is a front elevation view thereof;
1.3 is a rear elevation view thereof;
1.4 is a left side elevation view thereof;
1.5 is a right side elevation view thereof;
1.6 is a top plan view thereof;
1.7 is a bottom plan view thereof;
1.8 is a perspective view thereof in which an exemplary display module is exploded apart; and
1.9 is a perspective view thereof in which an exemplary display module is attached.

The broken lines shown in 1.8 and 1.9 depict exemplary environment of the steering wheel module for automobile that forms no part of the claimed design.
